(57) **CLAIM**

I claim the ornamental design for a cutting disc, as shown and described.

DESCRIPTION

1. Cutting disc
5. Cutting disc
- 1.1 :Front/top/right perspective view
- 1.2 :Front
- 1.3 :Rear/top/right perspective view
- 1.4 :Bottom
- 5.1 :Front/top/right perspective view
- 5.2 :Front
- 5.3 :Rear/top/right perspective view
- 5.4 :Bottom The left view is omitted because symmetrical to the right view; subject matter may be shown in broken lines for the purpose of illustrating portions of the cutting disc and forms no part of the claimed design.

1 Claim, 8 Drawing Sheets
